UNITED STATES PATENT OFFICE.

HANS HASS, OF BERGEDORF, NEAR HAMBURG, GERMANY.

STERN FRAME WITH BALANCED RUDDER FOR SHIPS.

Application filed April 1, 1927, Serial No. 180,270, and in Germany December 4, 1925.

My invention relates to an improved stern frame with a balanced rudder for use in connection with ships, particularly screw-driven ships.

5 Balanced rudders as hitherto constructed are usually mounted on a comparatively short, separate frame or post located in the rear of the propeller post and which does not extend over the full length of the rudder, the arrangement being such that the upper part of the rudder is pivotally mounted on gudgeons whilst a part of the body of the rudder extends towards the hull of the ship below the rudder frame or post.

15 It has also been suggested heretofore to interconnect the rudder post with the propeller post at the bottom thereof or by means of a bottom member so that the two posts form a single piece or frame, the rudder being pivotally supported in particular bearings provided for the purpose in the frame.

The former construction and arrangement are objectionable for the reason that the balanced rudder is supported on or over a comparatively short extent only and the short rudder post necessarily must be bulky and powerful in order to stand the stresses and strains inherent to a rudder of the stated type. The latter construction and arrangement heretofore suggested are objectionable for the reason that the provision of particular bearings in the frame for supporting the rudder body involves an excessive resistance of the ship to propulsion due to the formation of eddies.

30 The object of my invention is to remedy these defects and with this object in view I provide a stern frame forming a structure which is closed in itself so as to be of eminent strength and rigidity, and which is shaped at the same time with a view to avoid any resistances that might give rise to the formation of eddies. In a modification I even utilize the rudder for causing the current of water helically repelled from the propeller, to flow off in a direction parallel or approximately parallel as far as this is attainable, to the axis of the propeller shaft, whereby the efficiency of the propeller will be greatly increased.

35 With the above recited and other objects in view, reference is had to the following specification and drawings in which there are exhibited several examples or embodiments of the invention which are in no way, however, intended as a limitation upon the

scope of the appended claims as it is to be clearly understood that variations and modifications which fairly fall within the true scope of the said claims may be resorted to when found expedient.

40 In the accompanying drawings forming a part of this specification and showing for purposes of exemplification, as above stated, preferred forms and manner in which the invention may be embodied and practised:—

45 Figure 1 illustrates in side elevation a stern frame according to the present invention;

50 Figure 2 illustrates a section on the line II—II of Figure 1;

55 Figure 3 is a view similar to Figure 1, showing a modified embodiment of the invention;

60 Figure 4 represents a section on the line IV—IV of Figure 3 on a larger scale;

65 Figure 5 is an enlarged fragmentary view of the rudder showing another modification thereof;

70 Figure 6 is an enlarged sectional view on plane VI—VI of Figure 5; and

75 Figure 7 is a sectional view similar to Figure 2, representing a further modification of the rudder.

80 Where desirable the same reference symbols are used in the different figures to denote corresponding parts.

85 Referring to Figures 1 and 2, the balanced rudder 1 is mounted on or about a post 2 integral with the propeller frame 3 to form a strong and rigid closed structure. It will be seen in Figure 1 that the rudder post 2 is connected at the top with the frame 3 by a bridge piece 4 and at the bottom by a base piece 5. In accordance with the present invention the rudder is shaped to form a so-called stream-line body which completely surrounds or encloses the post 2.

90 In order to enable the rudder to be angularly displaced or turned to a sufficient degree without causing the metallic plates forming the skin 6 of the rudder to come in contact with the post 2, the latter is located so as to coincide with the axis A—A of the rudder. Preferably the rudder may be 95 pivotally mounted on the frame by means of gudgeons 7 and 8. To this end the rudder may be equipped with an eye for engagement with the gudgeon 8 or a separate vertical rod such as 10, see Figure 1, may be 100 employed, the said rod 10 extending vertically through the rudder and having an eye

9 at its bottom and in engagement with the gudgeon 8. As for the purpose of inserting or removing the rudder, when required, the lowermost part of the post 2 necessarily 5 must be undercut or bent inwards, as at 11 in Figure 1 and it will be of advantage to cut out the adjacent part of the sheet metal forming the skin 6 of the rudder, on the line indicated by 12 in Figure 1 and to substitute for the cut out portion a stationary sheet or plate structure 13 which is to be rigidly connected with the post 2 and the base piece 5 of the frame 3 so as to not follow the movements of the balanced rudder.

13 The body of the rudder comprises, as usually horizontal arms or struts 14 adapted to support the metallic sheets forming the skin 6, which are firmly connected with the said arms or struts 14 by means of rivets 20 or bolts. Care is to be taken that the skin 6 be prevented from coming in contact with the part 2, when the rudder is shifted into the one or the other extreme position, and to this end the rudder must be given a sectional area of sufficient width at those places where the skin is in close proximity to the post, so that there will always be a free gap between the post and the skin.

15 In some cases it will be advisable to give 30 the rudder post 2 a cross-sectional area as shown in Figure 2 where or so that the longer sides of the rectangular area denoted by 2 are situated perpendicular to the longitudinal axis of the ship, whereby a very 35 strong and durable construction of the post will be obtained. The frontal part 6^a of the skin 6 may be connected with the rear part thereof in any suitable manner, in the embodiment shown in Figure 2 the two parts 40 are interconnected by overlapping as at 6^b and reinforcing plates or sheets 15 are provided in the front part 6^a. The body of the rudder may be divided on a longitudinal vertical plane going through the center 45 thereof for the purpose of ensuring ready access to the bearing and rendering the rudder detachable from the post 2, I prefer, however, to divide the rudder body on a plane 50 rectangularly intersecting the said longitudinal plane, as above intimated.

16 In the embodiments shown in Figures 3 to 6 the gudgeons 7 and 8 are dispensed with and bearings 16 are provided in lieu thereof in the body of the rudder, the said bearings 55 16 being adapted to enclose and fit about corresponding bearing surfaces provided on the post 17 which is rigidly connected or integral with a base piece 18 of the propeller frame 19 so as to form therewith a closed 60 frame structure, just as hereinbefore described with reference to the corresponding parts 5 and 2 of Figure 1. Further the propeller frame shown in Figure 3 is provided with guiding surfaces 20 and 21 which 65 are shaped and adapted to impart a pre-

liminary torsion to the current of water flowing towards or into the propeller screw, so that the current of water will be discharged from the propeller screw in a direction approximately parallel to the axis of 70 the propeller shaft prior to its striking upon the vertical front edge 22 of the rudder. Thus owing to the stream-line shape or formation of the body of the rudder the current of water repelled by the propeller, will flow 75 in fore-to-aft direction without giving rise to the formation of prejudicial eddies.

17 In the modification illustrated in Figures 3 to 6 the metal plates constituting the skin or plating of the rudder are interconnected 80 by means of arms or struts 24 which preferably comprise a plate 25 with lateral flanges 26 and which are shaped to form the aforesaid bearings 16 co-operating with bearing surfaces on the post 17, as will be clearly seen in Figure 4. In this modification the body of the rudder is likewise divided on a plane B—B, see Figure 4, situated vertically to the fore-and-aft line of the rudder, the arms or struts 24 possessing a separate 85 frontal or fore part 27 and the bearing 16 being correspondingly split or divided. The two parts thus forming an arm or strut 24 are firmly connected with each other in any appropriate manner such as by bolts 28 or 90 95 the like.

18 In the modification of the balanced rudder shown in Figures 5 and 6 the two parts— 1 and 1^a, see Figure 1—are interconnected 100 in a different manner. The rear or aft part of the rudder body or the arms thereof are provided with bifurcated ends or projections and the front or fore part thereof is provided with single projections 31 adapted to engage between the shanks 30 of the 105 forked part for interconnecting purposes, cotters 29 engaging in suitable holes of the intermeshing projections serving to ensure an efficient, detachable connection between the parts.

19 Figure 7 illustrates a further modification of the rudder body in which the parts thereof extending below the propeller shaft and above the shaft are bent out of the longitudinal median plane of the rudder so as 110 to project towards the propeller in different directions, for the purpose of utilizing the lateral surfaces of the rudder for guiding and directing the current of water helically repelled by the propeller, in a manner that 115 the single water threads thereof will be given a tendency to flow approximately parallel to the axis of the propeller shaft, whereby the efficiency of the propeller screw will be greatly enhanced.

20 To this end the two lateral surfaces 32 and 33 of the upper half of the body of the rudder are differently shaped or curved and the corresponding surfaces 32^a and 33^a of the part of the rudder body below the axis 120 125 130

of the propeller shaft are of a similar configuration but in opposed relationship, as will be readily understood on inspection of Figure 7. The post 2 is enclosed within 5 the rudder body and may be widened to the same cross-sectional area as described with reference to Figure 2, in order to increase the strength and rigidity thereof.

The provision of a dividing joint in the 10 rudder body preferably vertically to the length thereof, or in other words, a rudder body consisting of two individual parts adapted to be disconnected, when required, as herein described and shown, involves valuable advantages. For the rudder can be 15 easily dismounted without interfering with the rudder post, and this may be done simply by removing the detachable front part thereof after the rudder has been turned 20 fully to port or starboard, whereby a further advantage is obtained inasmuch as sufficient space will be secured thereby for the removal of the propeller screw without requiring the rudder post to be removed or 25 the propeller shaft to be withdrawn inwards. This advantage is the more important as the usual guiding or directing surfaces as hitherto constructed in the rear of the propeller prevent the latter from being removed 30 in this way, since the said surfaces are located in close proximity to the blades of the propeller screw.

I have not attempted to explain all of 35 the minute details of the construction of the combined rudder and propeller frame, for it will be understood by those to whom this specification is addressed that the parts will be of the proper size and relationship and will be properly mounted, connected and 40 supported according to the tenets of naval architecture.

What I claim is:—

1. A rudder arrangement for ships comprising in combination a post supporting 45 a propeller shaft, a rudder post connected with said first mentioned post to form a closed frame, a balanced rudder having a stream line form enclosing said rudder post, and a rudder shaft rotatably mounted in 50 said closed frame and connected with the rudder.

2. A rudder arrangement for ships comprising in combination a post supporting a propeller shaft, a rudder post connected 55 with said first mentioned post to form a closed frame, a balanced rudder having a stream line form enclosing said rudder post,

and a rudder shaft rotatably mounted in 60 said closed frame and connected with the rudder, the axis of rotation of said rudder shaft substantially coinciding with that of the rudder post.

3. A rudder arrangement for ships comprising in combination a post supporting a propeller shaft, a rudder post connected with 65 said first mentioned post to form a closed frame, a balanced rudder having a stream line form enclosing said rudder post, said rudder consisting of two detachably interconnected parts, and a rudder shaft rotatably 70 mounted in said closed frame and connected with the rudder.

4. A rudder arrangement for ships comprising in combination a post supporting a propeller shaft, a rudder post connected with 75 said first mentioned post to form a closed frame, a balanced rudder having a stream line form enclosing said rudder post, said rudder consisting of two detachably interconnected parts, and a rudder shaft rotatably 80 mounted in the aforesaid closed frame and connected with the rudder, the axis of rotation of said rudder shaft substantially coinciding with the rudder post.

5. A rudder arrangement for ships comprising in combination a post supporting the propeller shaft, a rudder post connected with said first mentioned post to form a closed frame, a balanced rudder having a stream line form enclosing said rudder post 85 and consisting of two detachably interconnected parts, said parts comprising an aft part and a fore part, and a rudder shaft rotatably mounted in said closed frame and connected with the rudder.

6. A rudder arrangement for ships comprising in combination a post supporting a propeller shaft, a rudder post connected with said first mentioned post to form a closed frame, a balanced rudder having a 90 stream line form enclosing said rudder post, the two lateral surfaces of the rudder body being differently shaped for the purpose of guiding the water displaced by the propeller, the upper part of the body having the same 95 shape as the lower part of the body, the angle of said surfaces being oppositely formed with respect to the longitudinal axis of the rudder, and a rudder shaft rotatably 100 mounted in the aforesaid closed frame and 105 connected with the rudder.

In testimony whereof I affix herebelow my signature.

HANS HASS.
